CLAIM

The ornamental design for a wrist band data storage device, as shown and described.

DESCRIPTION

FIG. 1 is a bottom perspective view of a wrist band data storage device illustrating the new design;

FIG. 2 is a top perspective view thereof;

FIG. 3 is a right side view; where the left side view is not presented, as it is a mirror image of the right side view;

FIG. 4 is a top view thereof;

FIG. 5 is a bottom view thereof; and,

FIG. 6 is a rear view; where the front view is not presented, as it is a mirror image of the rear view.

In FIG. 1, the broken line showing an access window is for illustrative purposes only and forms no part of the claimed design.
